RAYMOND H. SULLIVAN, OF ROCHESTER, NEW YORK, ASSIGNOR TO NORTH EAST ELECTRIC COMPANY, OF ROCHESTER, NEW YORK, A CORPORATION OF NEW YORK.

GENERATOR REGULATION.

Application filed February 6, 1926. Serial No. 86,619.

This invention relates to regulators of the vibratory electromagnetic type, such as are used in connection with shunt wound electric generators to maintain a substantially constant voltage of output.

In regulators of the kind in question, it is common to provide two windings, one of these windings being connected constantly across the main terminals of the generator.

10 The other winding is utilized to increase the rapidity and regularity of vibration of the regulator, and for this purpose it is so connected, in one of several ways, as to act either as a "boosting" winding or a "bucking" winding, that is to say, its connections are such either that it assists the main regulator winding when the contacts of the regulator are closed, but not when they are open, or that it opposes the main winding when 15 the contacts are open, but not when they are closed. In either such arrangement the magnetic pull upon the armature of the regulator diminishes suddenly when the contacts are drawn apart, so that the armature 20 is immediately permitted to close the contacts again, and thus a rapid, steady vibration is maintained, affording a smooth and steady regulation of the generator.

The object of the present invention is to 30 achieve the same character of operation in a vibratory regulator, without the necessity of complicating its construction by the use of a divided winding, or two windings, on the magnet of the regulator. I have discovered that this may be accomplished by connecting the winding of the regulator in the manner hereinafter described and illustrated in the accompanying drawing.

The drawing is a diagram of an electric 40 system comprising a generator and a regulator connected in accordance with the present invention.

In the illustrated system a generator 1 is shown conventionally, having main brushes 45 or terminals 2 and 3, and a shunt field-winding 4. To secure a certain degree of inherent regulation, the shunt winding is shown as connected, at one end, with a third or supplementary brush 5 in a well known manner, 50 although this feature is not essential to the invention. The main conductors 6 and 7, connected with the main terminals 2 and 3, carry the current from the generator to any translating devices (not shown), such as 55 electric lights, a storage battery, etc.

The regulator comprises an electromagnet 8 and a pivoted spring-controlled armature 9. The armature cooperates with a fixed contact 10, and is connected, through a wire 11, with the main conductor 7 and thus with the main terminal 3 of the generator. One end of the field-winding 4 is connected as already described, while the other end is connected with one of the generator brushes, other than the brush 3, through two resistors 12 and 13, arranged in series with the winding.

When the voltage produced by the generator is at or below the desired amount, the current passes freely through the field-winding 4, by way of the regulator contacts and the wire 11, since these parts are connected in shunt around the resistors 12 and 13. Whenever the voltage rises above the desired amount for which the regulator is 70 adjusted, the magnet of the regulator causes the armature to open the contacts, thus throwing the resistors 12 and 13 into action to cut down the flow of current through the field-winding, and reducing the generated 75 E. M. F.

The magnet 8 of the regulator is provided, as shown, with a single continuous winding, of which one end is connected to the main conductor 6, and thus to the generator terminal 2. The other end of this winding is connected to the resistors 12 and 13 at the point of their mutual connection. This arrangement results in the following operation: when the regulator contacts are closed, 80 if it be assumed that the generator terminal 3 is positive, current will flow from the main conductor 7 through the resistor 13 to the regulator winding, and thence to the main conductor 6 and the main terminal 2. Current may also flow, from the conductor 7 through the wire 11 and the contacts of the regulator to the resistor 12, and thence through the regulator winding. Under 85 these conditions, therefore, the regulator is energized by a relatively strong current flowing through the resistors in parallel.

When the regulator contacts are separated, current can no longer flow to the regulator winding through the resistor 12, and the current which flows through the resistor 13 is divided, part of it flowing through the regulator winding, and the rest through the field winding of the generator. Accordingly, the current in the regulator magnet is 100 105 110

greatly reduced, and the armature is permitted immediately to close the contacts again, in the same manner as if the regulator were provided with a boosting or bucking winding.

While the resistors 12 and 13 are, for convenience, described as independent elements, it will be obvious that they need not be so constructed, but that the necessary connections may be made when using a single continuous length or winding of resistance wire, in which case the reference-numbers 12 and 13 may be understood to refer merely to the two parts into which the resistance material is divided by the intermediate connection with the regulator winding.

The foregoing arrangement entirely elimi-

nates the necessity of a divided or compound winding on the regulator, but accomplishes the same result without the use of any additional parts.

The invention claimed is:

The combination, with a generator having a shunt winding, of two resistors connected, in series, with said winding, and an electro-magnetic vibratory regulator having an armature, contacts, controlled by the armature, connected in shunt across said resistors, and a magnet with a single continuous winding connected, at one end, with a main terminal of the generator and, at the other end, with said resistors at their mutual connection.

RAYMOND H. SULLIVAN.
